UNITED STATES PATENT OFFICE

JAMES W. GASKILL, OF CANTERBURY, CONNECTICUT

CIGAR HOLDER

Application filed February 29, 1928. Serial No. 257,983.

The present invention comprehends the provision of a cigar holder embodying a stem supported prong adapted to penetrate the cigar at any appropriate point in its length, the smoke being conveyed through the prong and stem to the mouth of the user.

In carrying out the invention I contemplate a cigar holder of the above mentioned character embodying means for sealing the opening formed in the cigar by the prong, and thus prevent the escape of smoke except through the prong and stem.

More specifically stated, the invention embodies a stem upon which the cigar is firmly supported, the stem supporting a substantially curved plate upon which the cigar reposes, while projecting centrally from the plate is a pointed apertured prong, through which the smoke from the cigar is conveyed to the stem, the relative disposition of the plate and prong permitting the former to seal the opening made by the prong, so that smoke can not escape from the cigar without passing through the stem.

Another object of the invention resides in detachably associating the prong with the stem so that the entire holder can be quickly and conveniently cleaned with an ordinary pipe cleaner.

A further object of the invention resides in the provision of a cigar holder of the above mentioned character which embodies additional means cooperating with the aforementioned prong and supporting plate for firmly supporting the cigar upon the stem.

In one embodiment of the invention I contemplate the use of an adjustable clamp capable of accommodating cigars of different sizes, and arranged to cooperate with the prong to firmly support the cigar against casual turning or tilting movements with relation to the stem.

Other objects and advantages will appear when the following detail description is read in connection with the accompanying drawing and wherein like numerals of reference indicate similar parts in the several

Figure 1 is a side elevation of one embodiment of the invention showing a cigar supported thereon.

Figure 2 is a top plan view with the cigar removed.

Figure 3 is a sectional view on line 3—3 of Figure 1 with the cigar removed, and showing the open position of the clamping jaws by dotted lines.

Figure 4 is a side elevation of the modified construction showing a cigar supported thereon.

Figure 5 is a fragmentary plan view of a modified construction.

Figure 6 is a sectional view on line 6—6 of Figure 5 with the cigar removed.

Referring to the drawing in detail, and more particularly to Figures 1 to 3 inclusive 10 indicates a stem which may be of any suitable construction and also vary in size and configuration without departing from the spirit of the invention. The forward extremity of the stem is offset as at 11 and supports a collar 12 formed to provide a relatively broad substantially curved cigar supporting plate 13. The collar 12 may be permanently connected with the offset extremity 11, or it may be detachably secured thereto, being preferably threaded upon said extremity as illustrated in Figure 3. The collar is provided with a central threaded opening which passes through the supporting plate 13 to receive the hollow pointed prong 14, the latter being provided with suitable apertures 15. It is of course understood that the cigar 16 is adapted to 85

repose upon the curved supporting plate 13 with the pointed prong penetrating the cigar at any appropriate point in its length, so that the smoke from the cigar passes 90 through the pointed prong 14 into the stem 10. By reason of the relative location of the plate 13 with respect to the prong 14, the plate serves to effectively seal the opening in the cigar caused by the penetration 95 thereof by the prong 14, so that smoke can not escape from the cigar through this opening, without passing through the prong 14 into the stem 11.

Some suitable means is employed to co-

operate with the plate 13 and stem 14 to firmly hold the cigar upon the stem, in a manner to prevent casual tilting or turning of the cigar with relation to the prong. 5 In the specific embodiment of the invention illustrated in Figures 1 to 3 inclusive, this means is preferably in the nature of an adjustable clamp. The latter includes a pair of complementary curved clamping jaws 10 which are pivoted on a suitable pin 17 projecting from the opposed sides of the collar 12, and about which is arranged a coil spring 18 normally holding the clamping jaws in their closed positions. These jaws 15 are preferably constructed from flat resilient material and operate directly beneath the supporting plate 13, the jaws being constructed to lie substantially flush with the upper surface of said plate, in their normal 20 positions and thereby form in reality a continuity of said plate to provide a relatively broad bearing surface for the cigar 16. The material from which each jaw is constructed is cut away and the separated portion extended downwardly at an angle to the jaw to provide a finger engaging portion 19, these portions being divergently disposed so that they can be conveniently grasped to facilitate opening of the clamp as the occasion may require. It is manifest that the clamp can accommodate itself to cigars of different sizes, and if found necessary the clamping jaws may be slightly flexed for this purpose, inasmuch as they are constructed from bendable resilient material.

In practice the prong 14 is adapted to penetrate the cigar at some appropriate point in its length, approximately at a point between its ends, the cigar reposing upon 40 the supporting plate 13 and effectively embraced by the clamping jaws 20 so that the cigar is firmly held upon the stem against casual tilting or turning movements. After the cigar has been partially consumed, it 45 may be removed from the stem, and the prong 14 caused to penetrate the cigar adjacent one end thereof as illustrated in Figure 1. The construction permits of the use of a relatively long stem 10 so that the 50 smoke may enter the mouth of the user in a cool condition.

In Figures 5 and 6 inclusive I have shown a modified construction wherein the stem is indicated at 21 and which stem is also offset 55 at one end as at 22. Carried by this offset extremity is a collar 23 formed with a substantially curved supporting plate 24 used in the same manner as the plate 13 hereinabove described. Rising centrally from the 60 plate and communicating with the stem 21 is a hollow apertured prong 25 which conveys the smoke from the cigar through the stem to the mouth of the user. This form of the invention only distinguishes from the 65 above described embodiment in the means

employed for holding the cigar firmly positioned upon the stem. Instead of using a two-part adjustable clamp, this embodiment of the invention includes a sliding ring 26 adapted to receive the adjacent end of the cigar 27 as illustrated in Figure 4, the ring being formed with a small eye 28 which slides upon the stem 21, so that the ring can be moved toward and away from the adjacent end of the cigar as the occasion may require. In both forms of the invention the pointed prong is detachably associated with the stem, so that the entire device can be quickly and easily cleaned with an ordinary pipe cleaner.

While it is believed that the nature and advantages of the invention will be readily understood, I desire to have it known that I do not limit myself to what is herein shown and described and that such changes may be resorted to when desired as fall within the scope of what is claimed.

What is claimed is:

1. A cigar holder of the character described comprising a stem, a hollow apertured prong projecting therefrom and adapted to penetrate the cigar at an appropriate point in its length, a curved member supported by the prong and adapted to embrace the cigar at opposite sides of the prong for sealing the opening formed in the cigar by said prong, and relatively movable curved clamping jaws arranged at the opposite sides of said member forming a continuity thereof to embrace the cigar and cooperate with the prong for holding the cigar immovably positioned upon the stem.

2. A cigar holder of the character described comprising a stem, a hollow apertured prong projecting therefrom and adapted to penetrate the cigar at an appropriate point in its length, means for sealing the opening formed in the cigar by the prong, a pair of spring influenced complementary jaws pivoted at the opposite sides of the prong and adapted to embrace the cigar to hold the latter firmly positioned upon the stem and extensions projecting from the jaws whereby the latter are manipulated.

In testimony whereof I affix my signature.

JAMES W. GASKILL.
